UNITED STATES PATENT OFFICE

CHARLES W. WARNER, OF MIDDLETOWN, CONNECTICUT, AND THOMAS M. KEEFE, OF BOSTON, MASSACHUSETTS

DESIGN FOR A TUMBLER HOLDER

Application filed July 30, 1929. Serial No. 32,250. Term of patent 7 years.

To all whom it may concern:

Be it known that we, CHARLES W. WARNER and THOMAS M. KEEFE, citizens of the United States, residing, respectively, in Middletown, Middlesex County, Connecticut, and Boston, Suffolk County, Massachusetts, have invented a new, original, and ornamental Design for a Tumbler Holder, of which the following is a specification, reference being had to the accompanying drawings, forming a part thereof, and in which:

Fig. 2 is a front elevation;

Fig. 3 a top plan, and

Fig. 4 a cross-section on the line 4—4, Fig. 1.

We claim:

The ornamental design for a tumbler holder, as shown.

CHARLES W. WARNER.
THOMAS M. KEEFE.
